COUNTERBALANCED DOOR STRUCTURE

Filed Nov. 13, 1945

UNITED STATES PATENT OFFICE

2,425,365

COUNTERBALANCED DOOR STRUCTURE

Herman A. Davidson, Detroit, Mich., assignor to
The Aviation Corporation, New York, N. Y., a
corporation of Delaware

Application November 13, 1945, Serial No. 627,999

3 Claims. (Cl. 126—191)

1

The invention relates to door structures and more particularly to the type which includes a drop-door adapted to be swung manually into closed, ajar and open positions for use with ovens or oven-compartments.

One object of the invention is to provide a structure which includes a substantially vertical counter-balancing pull-spring which applies torque to the door and to a lever which coacts with a stationary cam-track for holding the door in different positions.

Another object of the invention is to provide an improved structure for drop-doors, which includes counter-balancing spring-means which requires relatively low torque, which is applied through a bell-crank lever to the door and a track with cams for holding the door in different positions.

Other objects of the invention will appear from the detailed description.

The invention consists in the several features hereinafter set forth and more particularly defined by claims at the conclusion hereof.

In the drawings:

Fig. 1 is a vertical section of a portion of a range with a drop-door structure embodying the invention, taken through the door adjacent one of its sides, on line 1—1 of Fig. 4, the door being closed.

Fig. 2 is a similar section illustrating the door in its open position.

Fig. 3 is a rear elevation of the hinge-structure, illustrating the door in its closed position, the oven liner being shown in section.

Fig. 4 is a section taken on line 4—4 of Fig. 1.

The invention is exemplified as applied to a range which includes a casing, generally designated 8, and is provided with an opening 9 for access to an oven or compartment 10 and a drop-door 11 for closing the opening. The door 11 is hingedly supported for swinging movements by a hinge-structure which comprises a vertically extending bracket 14 which may be formed of plate metal and is fixedly secured in any suitable manner, for example, by screws 15 to a structural member of the casing 8 at one side of the door-opening 9, and a bracket 19 which also may be formed of plate metal and is fixedly secured, in any suitable manner, for example, by rivets or screws 24 or welding to one of the side edges 20 of door 11. The door 11 is usually formed of sheet metal, with inner and outer walls. The bracket 14 on the casing is provided with an integral forwardly and downwardly extending arm or member 22, which extends through the

2

inner wall of door 11 and is connected by a pivot-pin 23 to the lower end of the bracket 19 on said door. Pivot-pin 23 between brackets 14 and 19 connects door 11 to the casing 8 for vertical swinging movement. Bracket 19 has a shoulder 18 which engages a stop-pin 17 carried by bracket 14 to limit opening movement of door 11 and to keep the same in a horizontal position so that it may be used as a shelf when inserting and removing articles from the oven.

The bracket 14 has a curved vertically extending rear edge 26 which functions as a track. Bracket 19 on door 11 is provided with an integral inwardly and downwardly extending arm or member 28 which projects from the inner face of the door, and alongside of the side face of bracket 14. A bell-crank lever 30 is fulcrumed at 31 on the inner end of arm 28 on bracket 19 and includes a downwardly extending arm or member 32 and an inwardly extending arm or member 34. A roller 36, journaled on a stud 37 which is mounted on the lower end of arm 32 of bell-crank lever 30, has a grooved periphery 38 which travels on the track 26 on the inner edge of stationary bracket 14. A pull-spring 40 has its lower end 41 connected, in any suitable manner, to a fixed part of the casing 8 and its upper end connected, as at 42, to the inner end of arm 34 of lever 30.

30 The track 26 is provided with a cam or hump 44 adjacent its lower end and a cam or hump 48 adjacent its upper end, over which the roller 36 will ride. The cam 44, when the door is swung ajar or to a partly open position, operates as an 35 abutment for roller 36 to which yielding torque is applied through lever 30, by spring 40 to hold the door ajar near its closed position. Cam 48 operates, when the door is being swung toward its horizontal position, as an abutment for roller 36 to yieldingly hold the door 11 against movement into horizontal position to prevent a sharp impact when the door reaches horizontal or way open position which would tend to break the hinges or clip the enamel parts, and as an abutment for roller 36 which is pressed by spring 40 against the track 26 at the upper end of said cam for resisting upward movement of the door when it has reached its horizontal position.

35 The operation will be as follows: during swinging movement of the door on the axis of pivot-pin 23, it will move fulcrum pin 31 for the bell-crank lever 30 in an arc concentric with said axis. Assuming the door is closed, roller 36 will be positioned at the lower end of the cam 44 on track 26. Yielding torque applied by spring 40

to arm 34 of lever 30, will press roller 36 against the lower portion of cam 44 and the latter will resist movement of the door from its closed position. The yielding torque provided by spring 40 and applied to fulcrum pin 31 will then also assist in holding the door in its closed position. During the initial opening movement of the door, the manual force applied thereto will swing arm 28 on bracket 19 to raise lever 30, and will, through fulcrum pin 31, cause roller 36 to ride over cam 44. When it is desired to hold the door ajar, the operator will release the door when roller 36 has passed over cam 44. The yielding torque applied to lever 30 by spring 40 will then hold roller 36 against track 26 at the upper end of cam 44, which will arrest the bodily downward movement of lever 30 and hold roller 36 so that the further upward movement of the door will be arrested. The door will then be held ajar or in a partly open position. When it is desired to lower the door to its horizontal position, it will be swung downwardly and roller 36 will ride on track 26. Engagement of roller 36 with cam 48 will yieldingly resist further opening movement of door 11 and act to prevent the operator from banging the door against the stop 17. After roller 36 passes over cam 48, the latter will function as an abutment for said roller against which it will be held by the yielding torque applied to lever 30 by spring 40 so that the door will be held in its horizontal position and the shoulder 18 against stop-pin 17.

The spring 40 extends approximately in a vertical direction to exert a vertically downward pull on arm 34 of lever 30 and applies yielding torque to said lever which is fulcrumed on arm 28 so that roller 36 will be yieldingly pressed against track 26 and yielding torque will be applied through fulcrum pin 31 to counter-balance the door.

During the lowering movement of the door, spring 40 will be extended to progressively increase the magnitude of its torque. To prevent an undesirable increase of resilient torque opposing the lowering movement of the door as it approaches its lowered position, cam-track 26 is of eccentric contour relatively to pivot-pin 23, with less eccentricity at the upper end of the track and greater eccentricity at its lower end. During the swinging movements of the door, the direction of pull of spring 40 remains approximately vertical. This is desirable so that it is not necessary to extend the spring to the rear portion of the oven. This construction provides a counter-balanced door, which moves smoothly during its swinging movements while the cams 44 and 48 on track 26 serve as abutments against which roller 36 is pressed for holding the door in its open, ajar and lowered positions.

The counter-balanced hinge-structure is illustrated at one side of the door, but may, if desired, be applied at both sides. If used at one side only, hinge-brackets 14 and 19 and pivot-pin 23, without the counter-balancing and holding mechanism, are provided at the opposite side of the door.

The invention exemplifies a counter-balanced door-structure adapted for oven-doors, which is simple in construction, which results in swinging movements of the door, and which includes a vertically extending cam-track and a bell-crank lever carrying a roller for engaging the track, which are adapted for use with a vertically extending pull-spring adjacent the front of the

oven. The structure may be easily installed in the casing.

The invention is not to be understood as limited to the details described, since these may be modified within the scope of the appended claims without departing from the spirit and scope of the invention.

Having thus described the invention, what I claim as new and desire to secure by Letters Patent is:

1. A door structure comprising, a casing having a door opening, a door for closing said opening, hinge brackets rigidly mounted on the casing and door, respectively, and pivotally connected for swinging movement of the door, the bracket on the door having an inwardly projecting arm, the bracket on the casing having a vertically extending curved track with cam-means on its inner edge, a bell-crank lever fulcrumed on the inner end of the arm on the bracket on the door, having a downwardly extending arm provided with means for engaging the track and an inwardly extending arm, and a spring between the inwardly extending arm on the lever and the casing for exerting yielding torque to swing the lever to engage the track and to exert lifting torque on the door.

2. A door structure comprising, a casing having a door opening, a door for closing said opening, hinge brackets rigidly mounted on the casing 30 and door, respectively, and pivotally connected for swinging movement of the door, the bracket on the door having an inwardly projecting arm, the bracket on the casing having a vertically extending curved track with cam-means on its inner edge, a bell-crank lever fulcrumed on the inner end of the arm on the bracket on the door, provided with a roller on a downwardly extending portion thereof for engaging the track, and a spring connected to the lever inwardly of the roller and to the casing for exerting yielding torque to swing the lever to hold the roller engaged with the track and to exert lifting torque on the door.

3. A door structure comprising, a casing having a door opening, a door for closing said opening, hinge brackets rigidly mounted on the casing and door, respectively, and pivotally connected for swinging movement of the door, the bracket on the door having an inwardly projecting arm, the bracket on the casing having a vertically extending curved track with cam-means on its inner edge, a lever fulcrumed on the inner end of the arm on the bracket on the door, and provided with means below the fulcrum for engaging the track, and a spring connected to the lever inwardly of the fulcrum for exerting yielding torque to swing the lever to engage the track and to exert a lifting torque on the door.
